UNITED STATES PATENT OFFICE

CHARLES A. MALSURY AND FLORENCE E. MALSURY, OF JOPLIN, MISSOURI

SHOE

Application filed March 6, 1930. Serial No. 433,570.

This invention relates to improvements in shoes, and has special reference to means for preventing the tongues of shoes from creeping or working toward one side, and for positively holding the tongues centered across the laced openings of the shoes.

It is a familiar fact within the experience of nearly every one that the tongues of shoes, which are intended to span the laced openings or slits at the front of laced shoes, and to cover the insteps of the wearers, and to protect the insteps from the pressure of the shoe laces and eyelets, often work or creep toward one side, leaving an uncovered space between one side edge of the tongue and the adjacent edge portion of the shoe upper. This is objectionable for many reasons. It leaves that portion of the instep of the wearer exposed and subject to the pressure of the shoe laces and eyelets, and also leaves a portion of the hosiery exposed to view between the side edge of the shoe tongue and the adjacent side edge of the shoe upper, thus detracting from the general appearance desired.

An object of the present invention is to provide means in connection with the shoe tongue, constructed and arranged to be engaged by the shoe lace in such a way as to hold the shoe tongue in the proper relationship and arrangement and positively prevent the shoe tongue from working toward either side.

Other objects of the invention will be apparent from the following description, reference being made to the accompanying drawing, in which—

Fig. 1 is a perspective view showing the invention in solid lines embodied in a shoe, outlined in broken lines.

Fig. 2 is a front elevation of a portion of the tongue having the lace-engaging members attached thereto.

Fig. 3 is a sectional view on the line 3—3 of Fig. 2.

Fig. 4 is an enlarged plan view with parts broken away, showing an appropriate construction of the lace-engaging members.

Fig. 5 is a plan view of a portion of a shoe tongue showing an alternative form of lace-engaging device attached thereto.

Fig. 6 is a sectional view on the line 6—6 of Fig. 5.

The shoe 1 is of familiar construction. The upper of this shoe has at its front a slit 2 provided with marginal portions 3 of the upper. A row of eyelets 4 extends along each marginal portion 3 and a shoe string or lace 5 is laced through the eyelets 4 in a familiar manner and for a well known purpose.

These shoes are provided with tongues often composed of a strip of leather 6 forming the front or outer surface of the tongue and a backing or lining 7 often composed of some textile fabric. The lining or reinforcement 7 is usually of slightly narrower width than the part 6, and these parts 6 and 7 are secured together by a row of stitches 8 extending through said parts near the marginal edge of the lining or reinforcement 7. The lower end of this tongue is attached to the shoe upper, leaving the side portions of the tongue detached from the shoe upper nearly throughout the length of the tongue. This tongue is of sufficient width to span the slit 2 when the shoe is worn and laced on the foot of the wearer. It is of sufficient width so that its side edges extend beyond the eyelets 4 in order to protect the foot of the wearer from the uncomfortable effect of the pressure of the shoe lace and the eyelets against the instep, which would occur if the tongue were not present to function as a shield. This tongue extends the full length of the slit 2, having its lower end below the lower end of said slit and its upper end usually slightly above the upper edge of the shoe upper.

It is a familiar fact that these tongues frequently work or creep toward one side or the other, thus exposing a part of the instep to the uncomfortable pressure of the shoe lace and shoe eyelets, and at the same time, creating a somewhat unsightly effect by exposing a part of the hosiery between one of the side edges of the tongue and the adjacent marginal portion 3 of the shoe upper.

The embodiment of the invention shown in Figs. 1 to 4, inclusive, comprises a pair of tongues having their outer ends attached to the marginal portions of the shoe tongue and

having their inner portions detached from the shoe tongue and provided with holes or eyelets through which the shoe lace 5 may be laced or threaded. Each of these tongues 5 comprises a section 9 of leather or the like forming the exposed front surface, and a reinforcing section 10 of some substantially non-elastic textile fabric secured and fastened to the section 9 by glue 11, or other appropriate fastening means. Two of these 10 lace-engaging tongues are attached to the shoe tongue by appropriate fastening means, such as stitches 12, passing through the lace-engaging tongues and through the shoe 15 tongue in the manner shown in Fig. 2. As there shown, the stitches 12 run along the marginal portion of the outer end of each of the lace-engaging tongues from the outer marginal portion of the part 6 of the shoe 20 tongue to the edge of the reinforcement 7 of the shoe tongue. These lace-engaging tongues extend inwardly toward each other, and each is provided with a series of holes 13 through which the shoe lace or string 5 may be passed in any suitable manner, as suggested by Fig. 1 of the drawing. These lace-engaging tongues are made of sufficient length so that the shoes may be worn by wearers having high insteps or by wearers 25 having low insteps, and so that the lace or string 5 may be passed through any appropriate ones of the holes 13.

In the variation of the invention shown in Figs. 5 and 6, the lace-engaging member 30 is composed of two thicknesses of material, including an outer or front piece 14 of leather or the like, and an inner lining or reinforcement 15 of substantially non-elastic fabric. These two members 14 and 15 are attached 35 together by glue 16 or other appropriate fastening means, and are attached to the shoe tongue by appropriately arranged stitches 17. This leaves the lateral marginal portions of this lace-engaging member detached from the shoe tongue, and through each of these 40 lateral marginal portions of the lace-engaging member a hole 18 is formed. Through the holes 18 the shoe lace or string 5 is intended to be passed in the manner indicated 45 in Fig. 5. The ends of the shoe lace are then tied or knotted so that the marginal portions of the lace-engaging member are at opposite sides of the knot or tie, thus positively preventing the shoe tongue from working laterally in either direction.

It is now clear that our invention obtains 50 all of its intended objects and purposes in a very efficient and economical manner. The provision of these pliable lace-engaging members in connection with the shoe tongue in no way interferes with the comfort and ease with which the shoe may be worn; but, on the contrary, these lace-engaging members increase the comfort and ease with 55 which the shoe may be worn, because it is im-

possible for the shoe tongue to work or creep toward either side and expose the foot of the wearer to the uncomfortable pressure of the shoe lace and shoe eyelets. The lace-engaging members may be made in numerous ways 70 and of various materials without departure from the nature and principle of the invention. We contemplate such variations as may be found appropriate, and without restricting ourselves in unessential particulars, we claim:—

1. In a shoe having a shoe lace and a shoe tongue at the inner side of the shoe lace, a lace engaging member comprising a front piece of pliable material and a piece of non-elastic pliable material attached to the inner 80 side of said front piece and cooperating therewith to form a tongue having holes therethrough for the passage of the shoe lace; and means for attaching one end of said lace engaging tongue to said shoe tongue.

2. In a shoe having a shoe lace and a shoe tongue at the inner side of the shoe lace, a lace engaging member comprising an outer ply of elastic pliable material and an inner 90 ply of non-elastic material attached to the inner side of said outer ply and cooperating therewith to form a lace engaging member having a lace receiving hole therethrough, and means for attaching said lace engaging member to said tongue at a distance from 95 said hole.

3. In a shoe having a shoe lace and a shoe tongue at the inner side of the shoe lace, a lace engaging member comprising an outer 100 ply of elastic pliable material and an inner ply of non-elastic material attached to the inner side of said outer ply and cooperating therewith to form a lace engaging member having a pair of spaced lace receiving holes therethrough, and means for attaching said lace receiving member to said tongue between 105 said holes.

4. In a shoe having a shoe lace and a shoe tongue at the inner side of the shoe lace, a lace engaging member comprising a piece of pliable material having a hole therethrough for the passage of the shoe lace, means for attaching one end of said lace engaging member to said shoe tongue, and non-elastic pliable means in connection with said lace engaging member preventing stretching and distortion of said lace engaging member.

CHARLES A. MALSURY.
